FASTENER

Florence M. Stader, Plymouth, Mich.

Application August 18, 1930, Serial No. 476,191

11 Claims. (Cl. 24—73)

This invention relates to fasteners and has particular reference to a fastening device adapted to hold lingerie straps from slipping off of the shoulders of the wearer.

5 One of the primary objects of this invention is to provide a fastener of the above mentioned character which will be simple in construction and which may be economically manufactured on a commercial scale.

10 A further object of this invention is to provide a fastener of the above mentioned character which may be detachably secured to a garment so that when the garment is laundered the fastener may be removed from the same.

15 Other objects and advantages of the invention will become more apparent as the following description proceeds, particularly when reference is had to the accompanying drawing, wherein:

Figure 1 is a fragmentary elevational view of a 20 garment showing fasteners constructed in accordance with the teachings of this invention associated with the same;

Figure 2 is a plan view of a blank from which a 25 fastener constructed in accordance with the teachings of this invention may be formed;

Figure 3 is a longitudinal sectional view through a fastener constructed in accordance with the teachings of this invention showing the same in position on a garment;

30 Figure 4 is a view similar to Figure 2 showing a slightly modified form of construction;

Figure 5 is a transverse sectional view through a fastener formed from the blank shown in Figure 4; and

35 Figure 6 is a view similar to Figure 2 showing a still further modified form of construction.

Referring then particularly to the drawing wherein like reference characters designate corresponding parts throughout all views, the numeral 10 designates a garment such as a dress or the like, while the numeral 11 designates an article of lingerie provided in accordance with the usual practice, with the shoulder straps 12. Associated with the shoulder portions 13 of the garment 10 are fasteners designated generally by the reference character 14, these fasteners being adapted to engage the straps 12 to prevent the latter from slipping downwardly off of the shoulders of the wearer.

50 The fasteners 14 may be conveniently formed from thin sheet metal stampings, and in Figure 2 one of these stampings is shown as comprising a strip of flat sheet metal stamped to provide a body portion 15 which is provided at its one end 55 with the transversely extending cuts or recesses 16

and 17 which open through opposite edges of the strip. Beyond the recess 17 the body portion of the fastener terminates in an end 18 provided with a boss or protuberance 19. At its other end the body portion 15 is provided with the transversely 60 extending cuts or recesses 20 and 21, the recess 20 opening through the same edge of the body portion 15 as the recess 17 and the recess 21 opening through the same edge of the body as the recess 16. The stamping also includes a flat elongated 65 hook portion 22 which is provided adjacent its free end with a transverse rib or boss 23, this hook portion being adapted to be bent on the line 24 to underlie the body portion 15, as clearly illustrated in Figure 3 of the drawing. It will be 70 noted that when the hook portion is thus bent on the line 24, the rib 23 thereof will underlie the boss 19 to form a substantially closed strap receiving pocket 25 between the body portion 15 and the hook portion 22.

75 For securing the fasteners to the garment there may be provided ribbons 30 sewed at their ends, as designated by the reference character 31, to the inner face of the garment 10 at the shoulders thereof. It will be understood that one ribbon 80 is associated with each fastener and by reference to Figure 3 of the drawing it will be noted that the ribbon extends over the portion 18 of the fastener, then through the slot 17 and under the portion 32 of the fastener, which portion is positioned between the recesses 16 and 17. The ribbon then 85 extends up through the recess 16 and over the body portion of the fastener and then down through the recess 20 under the portion 33 of the fastener, which is positioned between the recesses 20 and 21, and then up through the recess or cut 21. The recesses 17 and 21 are partially closed by projecting portions of the body of the fastener, these portions constituting means for holding the ribbon in these slots. It will thus be apparent 90 that the fastener may be engaged with the ribbon by first engaging one end thereof and by then pivotally swinging the fastener about the engaged end to engage the other end thereof. Thus, the fastener will be firmly but detachably fastened to 100 the ribbon in a position where its hooked portion 22 is adapted to hookingly engage the ribbon 12 of the article of lingerie. If desired, suitable eyelets 34 may be formed in the portions 32 and 33 of the fastener to provide means for permanently securing the fastener to the ribbon or shoulder seam of garment as by sewing or the like.

105 It is to be understood that the ribbon 30 may be sewed at its ends either directly to the garment, as illustrated in Figure 3 of the drawing, or that 110

this ribbon may be sewed at its ends to the free edge portions of the cloth of the garment beyond the shoulder seam thereof. In any event the ribbon will be permanently attached to the garment 5 while the fastener will be removably secured to the ribbon so that the same may be removed when the garment is laundered.

In Figure 4 of the drawing a slightly modified form of construction is shown in which the fastener is provided with the body portion 15', hook portion 22' and recesses 16', 17', 20' and 21'. In this form of invention, however, the body portion of the fastener is provided at points opposite the recesses 17' and 20' with the tabs 40 and 41 respectively, these tabs being provided with pointed detents 42 which extend angularly backwardly, as clearly shown in Figure 5 of the drawing.

In use, this fastener may be attached to a ribbon in the same manner as the fastener shown in Figure 2, and the tabs 40 and 41 may then be bent at the lines 43 and 44 respectively, to position the tabs in the manner illustrated in Figure 5 of the drawing, in which position the detents 42 will engage the ribbon to firmly clamp the fastener to the ribbon. Thus, the tabs constitute clamping members for securely anchoring the fasteners to the ribbons, which are in turn sewed to the garment. If desired, however, the ribbons may be eliminated and the fasteners engaged directly 30 with the free edge portions of the cloth adjacent the shoulder seams of the garment, in the manner clearly illustrated in Figure 5 of the drawing. When thus used, the fasteners will be positioned on one side of the free edge portions of the cloth 35 and the tabs 40 will then be bent backwardly to firmly clamp the fasteners to the free edge portions of the cloth, as will be readily understood. Thus, the fasteners disclosed in Figures 4 and 5 of the drawing may be secured to the garment 40 either directly as by attaching the same to the free edge portions of the cloth adjacent the shoulder seams or indirectly as by fastening the same to ribbons in the manner above described.

In Figure 6 a further modification of the inventive idea is disclosed in which the fastener is shown as comprising a single length of sheet metal designated generally by the reference character 50. This strip of metal is provided with a hook portion 51 adapted to be bent as at 52 to overlie the portion 53 which constitutes the body of the fastener. The portion 53 of this strip is provided with the laterally extending tabs 54 provided with detents 55 adapted to cooperate with suitable detents 56 on the body portion of the fastener whereby the fastener may be firmly clamped to the free edge portions of the cloth adjacent the shoulder seams of the garment.

From the above it will be apparent that the invention provides fasteners adapted for association 60 with a garment and adapted for engagement with the straps of an article of lingerie to prevent the straps from slipping downwardly off of the shoulders of the wearer. The fasteners may be either permanently or detachably secured to the garment and will be of simple construction whereby they may be economically manufactured on a commercial scale.

While the invention has been described with considerable detail, it is to be understood that the description is for the purposes of illustration only and that the right is reserved to make such changes in the details of construction and arrangement of parts as will fall within the purview 70 of the attached claims.

What I claim as my invention is:

1. A fastener of the character described comprising a sheet metal stamping bent upon itself to provide a body portion and a hook portion substantially parallel to said body portion, said body portion being provided at each of its opposite ends with a pair of slots opening through the edges thereof, one slot of each pair opening through one edge of said body portion and the other slot of each pair opening through the other edge thereof, said hook portion being provided with a protuberance adapted for engagement with a protuberance formed on said body portion. 80

2. A fastener comprising a sheet metal stamping bent upon itself to provide a body portion and a hook portion substantially parallel to said body portion, said body portion having a slot opening through one edge thereof to detachably receive a ribbon and said hook portion being provided with a protuberance adapted to abut a protuberance formed on said body portion. 85

3. A fastener comprising a sheet metal stamping having a body portion and a hook portion substantially parallel to said body portion and extending the length thereof, said body portion being provided with laterally extending clamping portions adapted to be bent upon the body portion to clamp the said body portion in engagement with a garment. 90

4. A fastener comprising a sheet metal stamping bent upon itself to form a body portion and a hook portion adapted for engagement with a lingerie strap, and fingers projecting laterally from the body portion of said fastener adapted to be bent to a position where they clamp the body portion of the said fastener to the free edge portions of the cloth of a garment beyond a seam thereof. 100

5. A fastener of the character described, comprising a sheet metal stamping bent upon itself to provide a body portion and a hook portion substantially parallel to said body portion, said body portion being provided with slots opening through one edge thereof adapted to removably receive a ribbon, said body portion having portions substantially closing said slots to retain the ribbon 110 in the same. 115

6. A fastener of the character described, comprising a sheet metal stamping bent upon itself to provide a body portion, and a hook portion substantially parallel to said body portion, said body portion being provided at each of its opposite ends with a pair of slots opening through the edges thereof, one slot of each pair opening through one edge of said body portion and the other slot of each pair opening through the other edge thereof. 125

7. A fastener having a body portion and a hook portion substantially parallel to said body portion and extending the length thereof, said body portion having a slot opening through one edge thereof to removably receive a ribbon. 130

8. As a new article of manufacture, a fastener having a body portion and a hook portion substantially parallel to said body portion, said body portion being provided at each of its opposite ends with a pair of slots opening through the edges thereof, one slot of each pair opening through one edge of said body portion and the other slot of each pair opening through the other edge thereof, and means for substantially closing certain of said slots. 140

9. As a new article of manufacture, a fastener having a body portion and a hook portion substantially parallel to said body portion, said body portion being provided with a plurality of pairs 145

of slots opening through the edges thereof, one slot of each pair opening through one edge of said body portion and the other slot of each pair opening through the other edge thereof.

5 10. A fastener of the character described comprising a strip of sheet material bent upon itself to provide a body portion and a hook portion substantially parallel to said body portion, said body portion being provided with a slot opening through one edge thereof and with slots on opposite sides of said first mentioned slot and opening through the opposite edge of said body portion whereby a ribbon may be threaded in said slots

by a winding of the ribbon about the body portion of the fastener.

11. A fastener of the character described comprising a strip of sheet material bent to provide a body portion and a hook portion, said body portion being provided with at least three slots opening through the edges thereof, alternate slots opening through opposite edges of said body portion whereby a ribbon may be threaded in said slots by a winding of the ribbon about the body portion of the fastener. 80 85
